2 SHEETS—SHEET 2.

UNITED STATES PATENT OFFICE.

CHARLES CORER, OF FORREST CITY, ARKANSAS.

ADJUSTABLE BEDSTEAD.

1,383,907.

Specification of Letters Patent.

Patented July 5, 1921.

Application filed March 1, 1917. Serial No. 151,775.

To all whom it may concern:

Be it known that I, CHARLES CORER, a citizen of the United States, residing at Forrest City, in the county of St. Francis and 5 State of Arkansas, have invented certain new and useful Improvements in Adjustable Bedsteads; and I do hereby declare the following to be a full, clear, and exact description of the invention, such as will enable 10 others skilled in the art to which it appertains to make and use the same.

The invention relates to improvements in bedsteads.

The object of the present invention is 15 to improve the construction of bedsteads, and to provide a simple, practical, and efficient bedstead of strong, durable and inexpensive construction capable of ready adjustment to arrange it either as a single 20 or double bed for accommodating one to three persons and adapted to form a firm and secure structure in either adjustment without necessitating the removal of any of the parts so that the latter will not become 25 lost or misplaced and thereby interfere with a quick change of the adjustment of the bedstead.

With these and other objects in view, the invention consists in the construction and 30 novel combination of parts hereinafter fully described, illustrated in the accompanying drawings and pointed out in the claim here-to appended; it being understood that various changes in the form, proportion, size 35 and minor details of construction, within the scope of the claim, may be resorted to without departing from the spirit or sacrificing any of the advantages of the invention.

40 In the drawings:

Figure 1 is a plan view of a bedstead constructed in accordance with this invention and shown arranged as a double bed.

Fig. 2 is a similar view, the parts being 45 arranged to form a single bed,

Fig. 3 is a vertical transverse sectional view taken on line 3—3 of Fig. 1,

Fig. 4 is a vertical transverse sectional view taken on line 4—4 of Fig. 2,

50 Fig. 5 is a longitudinal sectional view of the bedstead,

Figs. 6 and 7 are detailed sectional views illustrating the manner of connecting the pivoted links to the corner posts, and

55 Figs. 8 and 9 are detailed sectional views illustrating the construction of the panel

plates and the arrangement of the inner ends of the pivoted links.

Like numerals of reference designate corresponding parts in the several figures of 60 the drawings.

In the accompanying drawings in which is illustrated the preferred embodiment of the invention, the adjustable bedstead comprises in its construction corner posts 1 65 which may vary in length at the head and foot of the bedstead or be of the same length as illustrated in the accompanying drawings. The corner posts are connected at the sides of the bedstead by rails 2 having an 70 interlocking connection 3 of the ordinary construction to enable the ends of the rails 2 to be connected with and disconnected from the corner posts. The rails may be of any desired form and the corner posts are 75 connected by transverse links 4 pivoted together at their inner adjacent ends by bolts 5 and connected at their outer ends to the corner posts by pivot bolts 6. The links 4 are arranged in pairs and the corresponding 80 members of the several pairs of links are disposed in parallelism and are adapted to swing downwardly from the horizontal position, illustrated in Fig. 3 of the drawings, to the inclined position shown in Fig. 4 to 85 permit the corner posts to be arranged closer together to change the bedstead from a three-quarter or double bed to a single bed. The corner posts are provided with slots 7 through which the outer ends of the links 90 pass and the outer ends are preferably limited in their upward and downward movements by the upper and lower walls of the slots 7. Bolts, rivets or other suitable fastening devices may be employed for pivot- 95 ally connecting the links together and also to the corner posts and the inner adjacent ends of the links are arranged between inner and outer vertical panel plates 8, which connect the several pairs of links and cause the 100 same to move in unison. The panel plates, which are arranged in pairs at the inner and outer faces of the said links, are adapted to prevent the occupants of the bed from coming in contact with the joints and they also 105 prevent contact with the joints exteriorly of the head and foot boards of the bed. Also the panel plates are adapted to rest upon the floor when the bedstead is adjusted inwardly to form a single bed. The head and 110 foot of the bed are preferably equipped with telescoping members 9 and 10, which form

a neat finish at the top of the head and foot of the bed, and also assist in the guiding of the same in opening and closing the bedstead.

5 The bedstead is firmly secured in its adjustments by means of inner and outer connecting rods or members 11 and 12 arranged in pairs and located at points intermediate of the ends of the bedstead and at the ends 10 of the same. Each of the connecting rods or members is hinged at one end at 13 to one of the side rails and is provided at its other end with a hook 14 adapted to engage an eye or opening 15 in the opposite side rail. The 15 inner rods are shorter than the outer rods and while a pair of each of the said rods or members is shown the number may of course be varied and when one set of rods or members is in use the other set is arranged at the inner faces of the side rails and the hooks are preferably engaged with eyes 16 and 17 for holding the rods or members snugly against the side rails.

It will be seen that the extensible or adjustable bedstead may be easily and quickly 25 changed from one size to the other and that the parts are rigidly held in their adjust-

ments. The telescoping members 9 and 10 may be clamped with a set screw as shown if desired.

What is claimed is:

An adjustable bedstead comprising foot and head posts each of hollow formation and having slots, side rails connecting the foot and head posts together, pairs of links 35 having their outer ends pivoted to said posts within the slot and limited in their upward and downward movements by the upper and lower walls of said slots, pivots connecting the inner ends of the pairs of links together, 40 panels connected to said pivots on opposite sides of the links and adapted when in one position to engage the floor for aiding in supporting and limiting the movement of said links, and adjustable securing means 45 between the pair of head posts and the pair of foot posts.

In testimony whereof I affix my signature in presence of two witnesses.

CHARLES CORER.
